SAFETY SUSPENSION DEVICE

Arnold J. Schultz, Bellport, N. Y., assignor to Simplex Safety Block Co. Inc., New York, N. Y., a corporation of New York

Application December 24, 1941, Serial No. 424,233

6 Claims. (Cl. 254—192)

This invention is directed to a safety device which is adapted to be used in the suspension of life-boats, scaffolds and the like, so as to enable the occupants thereof to manipulate their position with full control of the boat or scaffold.

In such devices and especially in life-boats, which are hung from davits, considerable difficulty arises when it is necessary to lower the boats. It has been customary to cause the lowering by hand manipulation of ropes by at least two individuals aboard the vessel, their actions lowering the life-boats to the water. Considerable difficulties arise in that since each individual controls one end of the boat, it is most difficult to lower both ends equally, particularly as when the boat is part-way down from the vessel, it is no longer visible to the operators aboard the vessel. Therefore, very often a boat is capsized before it reaches the water. Also, it is impossible for the operators to slowly and uniformly lower the boat so that many accidents occur by reason thereof, especially at night.

In order to overcome these disadvantages, it is highly desirable that a device be provided which is located within the boat itself and which can be manipulated by the occupants of the boat, who are in a position to determine at all times exactly how the lowering should be conducted. It is also desirable that the control of the lowering be so simple that even inexperienced persons are capable of manipulating the same.

It is therefore among the objects of the present invention to provide a device which may be attached to a boat, scaffold, or the like and which will render it a simple matter for the occupant to lower the device at any desired speed, and with perfect control.

It is also among the objects of the present invention to provide a device which is simple in construction, contains but a few parts, which is sturdy, and which may be readily inserted in operative position.

In practicing the present invention, there is provided an elongated block, usually of cast metal such as bronze or of malleable iron. Integrally formed therewith is a brake face, and a pivoted cam cooperates therewith to grip a rope, cable, or the like. A handle formed on the cam is so arranged that the action of gravity normally forces the cam into the gripping position. Upward movement of the handle by the operator will release the rope to the desired extent and by continued manipulation, the speed of movement of the rope and consequently of the boat or the like, can be accurately and closely controlled.

In the accompanying drawing, constituting a part hereof and in which like reference characters indicate like parts:

Fig. 1 is a perspective view of my device in operative position, showing the manner in which the ropes are associated therewith to give the desired results;

Fig. 2 is a horizontal cross-sectional view thereof, taken along the line 2—2 of Fig. 1;

Fig. 3 is a fragmentary vertical cross-sectional view, taken along the line 3—3 of Fig. 2; and

Fig. 4 is a perspective view of a modified form of the device, shown in Fig. 1.

The device consists essentially of a block having lateral faces 1 and 2, a front face 3 and a rear face 4. As shown in Fig. 1, the block is elongated and has at the lower end 5 thereof, an opening 6 whereby the device may be attached to a boat, platform, or the like. At the upper end 7 of the block, there is usually provided an opening 8 whereby a rope may be secured to the top of the device.

Within the block and at a central portion thereof, there is an opening 9 extending from front 3 to back 4 of the block. A pulley 10 is pivoted on axis 11. Below said pulley and above opening 6 and extending laterally from the block, is the member 12 formed integrally with the block and having a brake face 13 therein. Sides 14 and 15 thereof extend forwardly and hold in pivoted position by axis 16, a cam 17 recessed as shown at 18. The face of the cam is formed with corrugations 19 to better grip a rope.

Extending downwardly from the cam and integral therewith, is a handle 20 which in the position shown, is vertical. The cam is in gripping position. The weight of the handle 20 is substantially greater than the weight of the cam 17, so that the action of gravity tends continually to hold the cam in gripping position.

In operation, a rope 21 is secured to an upper block which is held on the davit or the like, the rope extending at 22 downwardly under pulley 10, then extending upwardly as shown at 23, over the pulley of the upper block, and then downwardly as shown at 24, around and over the snubbing-post 25. Said post extends laterally from side 2 of the block, the upper surface being approximately on the same level as the top of pulley 10. The rope then passes downwardly as shown at 26, through the space between face 13 and cam 17, and out as shown at 27, the free end of the rope resting in the boat or the like.

In suspending a boat from the davits, two such blocks are used, one at each end of the boat, as

will be apparent. In order to lower the boat, an operator standing at each end grasps the handle 20 and moves it forwardly and upwardly, relative to the block, thereby releasing the rope 26, the weight of the boat then causing slipping of the rope through the brake, snubbing-post and pulleys. The two operators may, by shifting the handle backward and forward, control the speed of movement of rope 26 or arrest it as desired. Such control is very simple and does not require any great effort on the part of the operators. If the operators should drop the handles then the brake automatically locks the boat in place.

In Fig. 1 a rope 28 is shown as passing through opening 6. It may be used for securing to the boat or the like. However, in many cases, a hook is provided which replaces rope 28 and may be inserted into opening 6.

As shown in Fig. 1, the opening 8 is not used. It is provided in case the boat block on the davit has two pulleys instead of one. In such case, the end of rope 21 is tied in opening 8. It then passes over one of the pulleys of the boat block, down under pulley 10, then upward over the second pulley, and then downwardly as shown at 24, 25 26 and 27.

In Fig. 4 there is shown a modification of the device in which there is provided a block 30 of elongated form, having vertical partitions 31 extending from front to back, and defining three openings in which pulleys 32 are mounted.

To the lower end 35 of block 30 is secured a hook 36. This may be formed integrally with the block. It is adapted to hold a ring 37 or other element which supports the boat or the like. Extending laterally from portion 35 at side 33 are members 38, similar to members 14 and 15 of Fig. 2. A cam 39 is pivoted at 40 and cooperates with a brake face (not shown) similar to face 13.

A handle 41 integral with cam 39 extends in a horizontal direction and, as shown in Fig. 4, is slightly above the horizontal. A knob 42 on the extreme end thereof, provides suitable weight to force cam 39 into the gripping position as shown in Fig. 4, by the action of gravity. In many cases, particularly in certain types of life-boats where the covers thereof extend up to hook 36 or opening 6, if the handle in the gripping position extended downwardly, there might be interference with the placing and the removal of the cover. Therefore, as shown in Fig. 4, the handle may be made to extend substantially horizontally and thus avoid such a difficulty.

In the prior art it has been attempted to obtain results of the type described herein, but the devices suggested for the purpose have been entirely inadequate. In one such device there was provided a relatively long member which was pivoted and which was intended to be pressed against a rope by hand in order to modify the speed of the rope. However, this did not operate by a cam action and normally there was no gripping of the rope by the device. Furthermore, it was necessary that the pressure exerted by the operator be sufficient in order to give the clamping action. In another device for the same purpose, there was provided a cam arrangement of complicated character having a spring device which normally held the cam in gripping position. It was necessary, by hand manipulation, to overcome the pressure of the spring. This device had numerous disadvantages in that there was no certainty of the operation of the spring device and the entire structure was fabricated of

a considerable number of parts, so that the strength thereof was inadequate. It was liable to be injured by even moderate blows and it was incapable of withstanding the corrosive action 5 of weather on the various assembled parts.

Although the invention has been described, setting forth two embodiments thereof, it is apparent that changes may be made in the details of the construction within the spirit of the invention. For instance, the exact form and shape of the blocks as well as the size thereof, may be varied at will. It is essential that the relative arrangement of the brake, snubbing-post and pulley be as shown, but variations in the detail of construction may be made. One of the sides 14 or 15 may be open so that a rope may be slipped into the brake. While it is preferred that the entire block and associated parts be cast or forged or otherwise integrally formed, it is of course possible to modify the construction and form the same of a greater number of parts. However, the simplicity and unitary construction is highly desirable for service wear. In view of the above, the invention is to be broadly construed and not to be limited except by the claims appended hereto.

What is claimed is:

1. Safety device for boats, scaffolds, and the like comprising an elongated solid unitary block, 30 means formed in the lower end thereof for attachment to a device to be supported, a brake face extending laterally from said block and formed integrally therewith, a cam held laterally from said block and pivoted in said extension and adjacent to said face, a handle rigidly secured to said cam, said face and cam adapted to clamp a flexible member therebetween, the weight of said handle under the action of gravity acting to clamp said flexible member against 40 movement, and a snubbing-post extending laterally from said block above said face in vertical alignment therewith to hold said flexible member in operative relation with said cam, the manipulation of said handle being adapted to allow continuous and variable movement of said flexible member.

2. Apparatus as described in claim 1 wherein a lateral hole is provided at the upper end of the block for the attachment of a flexible member and wherein an enlarged lateral hole at the lower end of the block provides said means formed in the lower end of the block for the attachment of the device to be supported.

3. Safety device for boats, scaffolds, and the like comprising an elongated solid unitary block, means formed in the lower end thereof for attachment to a device to be supported, at least one pulley pivoted within the body of said block on a horizontal axis in the central portion thereof, a brake face below said pulley extending laterally from said block and formed integrally therewith, a cam held laterally from said block and pivoted in said extension and adjacent to said face, a handle rigidly secured to said cam, said face and cam adapted to clamp a rope therebetween, the weight of said handle under the action of gravity acting to clamp said rope against movement, and a snubbing-post extending laterally from said block above said face in vertical alignment therewith to hold said rope in operative relation with said cam, the manipulation of said handle being adapted to allow continuous and variable movement of said flexible member.

4. Safety device for boats, scaffolds, and the

like comprising an elongated solid unitary block, means formed in the lower end thereof for attachment to a device to be supported, at least one pulley pivoted within the body of said block on a horizontal axis in the central portion thereof, a brake face below said pulley extending laterally from said block and formed integrally therewith, a cam held laterally from said block and pivoted in said extension and adjacent to said face, a handle rigidly secured to said cam, 10 said face and cam adapted to clamp a rope therebetween, the weight of said handle under the action of gravity acting to clamp said rope against movement, and a snubbing-post extending laterally from said block above said face in 15 vertical alinement therewith to hold said rope in operative relation with said cam, the upper surface of said snubbing-post being in substantially horizontal alinement with said pulley, the manipulation of said handle being adapted to allow continuous and variable movement of said flexible member.

5. In a safety device which is adapted to permit continuous and variable descent of a device supported by a rope, the combination of, an elongated solid unitary block adapted to be held in a vertical position and having attaching means at the lower end thereof, a bracket extending laterally from said block and formed integrally therewith, said bracket having a pair of spaced ears with a brake face therebetween, a cam member pivoted between said ears and having a cam surface adjacent said brake face to cooperate therewith in exerting a variable clamping action on a rope passing therebetween, said cam member having an extended handle portion which is moved toward the downward vertical position during the action of clamping a rope between said cam surface and said brake face whereby the weight of the handle tends to 20

cause the rope to be clamped, a snubbing post extending laterally from said block above said bracket for cooperating with the rope, and a pulley mounted within said block above the center of the block with the block recessed and the pulley of such a size that a rope passing downwardly and about said pulley and thence upwardly again passes free of the two sides of the block.

6. A safety device of the character described comprising, an elongated solid unitary block having means at one end thereof for attachment to a device to be supported, a bracket extending laterally from said block and formed integrally therewith, said bracket having a pair of ears whereby the bracket is substantially U-shaped with a brake face on the inner surface of the base of the U, a cam member pivoted between said ears and having a cam portion with a cam surface adjacent said brake face to cooperate therewith in clamping a rope extending therebetween, said cam member having a handle rigidly secured to said cam portion and so related to said cam surface that the weight of the handle under the action of gravity acts to clamp the rope, a pulley mounted in a recess in said block spaced longitudinally of the block above the level of said bracket extension, and a snubbing post extending laterally from said block above said bracket for cooperating with the rope, whereby said block is held in an upright position by the opposed forces of the device to be supported at the lower end of the block and of the combined action of a rope extending through said pulley and the rope acted upon by said cam member and whereby the manipulation of said handle allows continuous and variable movement of the rope.

ARNOLD J. SCHULTZ.
